(57) **CLAIM**

The ornamental design for an awning opening-closing structure, as shown and described.

DESCRIPTION

FIG. 1 is a view of an awning opening-closing structure shown in from the front with the present disclosure, FIG. 2 is a view of the awning opening-closing structure shown in from the rear, FIG. 3 is a view of the awning opening-closing structure shown in from the left;

FIG. 4 is a view of the awning opening-closing structure shown in from the right; FIG. 5 is a view of the awning opening-closing structure shown in from the top;

FIG. 6 is a view of the awning opening-closing structure shown in from the bottom; FIG. 7 is a perspective view of the awning opening-closing structure shown in from the front; and,

FIG. 8 is a view of the awning opening-closing structure shown in at an expanded state. The broken lines and the half-tone areas within the broken lines depict portions of the awning opening-closing structure that form no part of the claimed design.
